MEASURING BOARD OR CHART FOR PORTABLE GARMENT DRIERS

Blaine Kelley, Charlotte, N. C.

Application September 13, 1928
Serial No. 305,803

1 Claim. (Cl. 33—2)

This invention relates to certain new and useful improvements in measuring boards or charts for portable garment driers or the like and has for its primary object to provide a measuring chart 5 to determine the exact dimensions of a garment such as its length, bust, waist and sleeve measurements before being cleaned so that when the garment is placed on the portable drier, the same may be stretched, if shrunk during the cleaning 10 operation, to its original dimensions to insure delivery or return of the garment after the cleaning operation in its original size.

In addition, the chart may be used for measuring garments separate from a cleaning or drying 15 apparatus, such as in the tailoring art, and in each instance after measurements are taken of the original garment, a card or tag to be attached to the garment carries indicia that may be suitably marked to determine various proportions or 20 measurements of the garment.

With the above and other objects that will become apparent as the nature of the invention is better understood, the same consists of a novel construction, combination and arrangement of 25 parts to be more fully described in detail and then claimed.

In the accompanying drawing which shows the preferred embodiment of the present invention,

Figure 1 is a front elevational view of a chart 30 or measuring board for a garment for use in connection with a portable garment drier showing the suspended garment in dotted line position for determining bust and waist measurements and in full line position for determining the length of 35 the garment and sleeves.

Figure 2 is an edge elevational view of the measuring chart.

Figure 3 is a plan view of a garment tag having length, bust, waist and sleeve measurements 40 printed thereon to be properly marked and associated with the garment to be later cleaned.

The measuring chart comprises a standard 1 supported upon feet 2 with a measuring chart or board 3 suitably secured to the standard 1 adjacent its upper end. The measuring face of 45 the board may be finished in any desired material, preferably of a waterproof nature and is crosslined as at 4 both horizontally and vertically representative of linear measurements, the vertical lines preferably indicating half inch 50 measurements while the horizontal lines represent one inch measurements, the upper edge of the board 3 and the left side thereof having printed or otherwise impressed thereon spaced 55 graduations 5.

Before cleaning the garment G, the same is

first measured as illustrated in Figure 1 so that should any shrinkage occur during the cleaning operation, the garment may be thereafter stretched to its normal measurements. The garment G is suspended over the face of the chart or board 3 by the hanger 6 that is engaged by a hook 7 carried by the chain 8 which passes over the pin 9 at the upper end of the standard 1 with the end of the cord or chain 1 anchored as at 10 to the upper edge of the measuring board. 65 The transverse measurements on the board extend or begin from the right hand side thereof while the length measurements begin at the upper end thereof and in order to obtain a bust or waist measurement of the garment G, the 70 latter is shifted laterally as indicated by dotted lines in Figure 1 to obtain the correct measurements. When the garment is vertically suspended as illustrated by full lines in Figure 1, the length of the garment and also the sleeves 75 is determined, it being noted that the standard 1 is graduated in inch measurements as at 11. A block 12 is carried by an upper corner of the measuring board 3 with a pencil 13 suspended therefrom, the block 12 carrying a pin 14 upon 80 which the garment tag 15 shown in Fig. 3, is suspended. The garment tag 15 is vertically 85 lined and captioned to represent measurements of the garment comprising the length, bust, waist and sleeve measurements with each column 90 of the garment tag having suitable characters printed designating standard measurements with spaces for special measurements. The several garment measurements may be either checked opposite the desired character or the 95 card perforated with a hand punch so that after the garment has been cleaned, original measurements thereof are found on the garment tag 100 associated therewith.

While there are herein described the preferred 105 embodiments of the invention, it is to be understood that various changes may be made in details of construction and also in the use of the invention, such as will fall within the scope of the invention as claimed.

What I claim as new is:

Garment measuring means comprising a graduated standard, a cross lined chart suspended from the upper end of the standard with the standard graduations located below the lower end of the chart, means for holding a garment in front of said chart whereby its measurements may be read from the chart and the over-all length of the suspended garment extending below the chart may be determined.

BLAINE KELLEY.
